Primary Examiner — Eric Goodman*Assistant Examiner* — Luqman McNeil*(74) Attorney, Agent, or Firm* — Dale F. Regelman; Quarles & Brady LLP(57) **CLAIM**

The ornamental design for a display screen or portion thereof with icon, as shown and described.

DESCRIPTION

The file of this patent contains a least one drawing executed in color. Copies of this patent with color drawings will be provided by the United States Patent and Trademark Office upon request and payment of the necessary fee.

The FIGURE is a front view of a display screen or portion thereof with icon showing our new design.

The broken lines are included to illustrate a display screen portion that forms no part of the claimed design.
